UNITED STATES PATENT OFFICE.

JAMES S. KENNEDY, OF YONKERS, NEW YORK.

AUTOMATICALLY-CONTROLLED WATER-GAS SET.

Application filed December 21, 1921. Serial No. 524,038.

To all whom it may concern:

Be it known that I, JAMES S. KENNEDY, a citizen of the United States, residing in Yonkers, county of Westchester, State of 5 New York, have invented a certain Improvement in an Automatically-Controlled Water-Gas Set, of which the following is a specification.

The present invention has relation to a 10 water gas set, and more particularly to the means for automatically controlling the operation of the water gas set.

This application is in part a continuation 15 of my earlier copending application Serial No. 427,706, filed December 2nd, 1920.

As is well known, the making of carburetted water gas involves a cycle of operations, comprising generally a series of alternate "blows" and "runs". During the 20 "runs", the basic gas is being formed by the passage of steam through a mass of incandescent fuel, by which it is decomposed. During the "blows" air is being forced through the fuel mass to restore the 25 temperature lost during the decomposition of the steam.

Besides the valves controlling passages of the air and steam, it is necessary to operate in proper sequence the stack cap, the oil admission for enrichment of the basic gas in the carburetter and the mutually connected upper and lower "hot valves" which determine the direction (up or down) of flow through the fuel.

35 The total length of time occupied by a complete cycle of operation will vary with variations in a number of conditions; and such variations will also determine the proportions of the total time occupied by each 40 "blow" and "run", as well as the proper moment for admitting and cutting off oil and for reversing the direction of the flow of steam by moving the "hot valves". The determination of these various factors is the 45 function of a gas engineer, and, where all of the successive and inter-related valve movements are accomplished manually, the closest supervision of labor is rendered necessary. Indeed it is virtually impossible to 50 insure perfect compliance at all times with the rules for operation laid down by the engineer. Besides this, careless operation sometimes causes accidents which are dangerous to life and property.

55 The present invention supplies means capable of easy application to existing types

of water gas sets or plants, whereby all of the complicated operations above mentioned may be automatically controlled and timed with complete certainty and entire accuracy. 60 The utmost flexibility of operation is possible, so that the order of operations and the time occupied by each is capable of quick and easy determination by an engineer, who merely has to set the mechanism for the particular operation deemed necessary at any time. Once set, the device can be relied upon to bring about a succession of cycles of the desired character, without possibility of mistake or accident. In its preferred 65 form, my system involves a complete interlocking, whereby no particular operation can be carried out without the previous occurrence of such other operations as should properly anticipate it. The invention also 70 includes a complete protective system to insure safety, whereby the water gas set is automatically shut down and placed in a safe condition upon failure of an operation to take place successfully at its appointed 75 time, or in case of accident or emergency. 80

My apparatus possesses also the advantage that it does not merely determine the proportions of a fixed total time which are occupied by each "blow" and "run" successively. In my system the total length of a 85 cycle may be varied at will within any pre-determined limits, and thus certain definite and independent time periods can be assigned to the blows and runs respectively. 90

A further important feature of this invention is found in means whereby the entire automatic system may be rendered inoperative (but only in the shut down position) while enabling an engineer to operate 95 the set manually in accordance with special conditions; or, if desired to operate one or more valves by themselves. These means are so interlocked with the automatic apparatus as absolutely to prevent either system interfering with operation of the other. 100

Other novel and advantageous features of the invention will appear hereinafter.

A preferred embodiment of the invention is illustrated in the accompanying drawings, 105 wherein Figures 1, 1^a, and 1^b, are diagrams in elevation and partly in section showing the relation of the controller proper to the apparatus for opening and closing the various master valves, Figures 2, 2^a, and 2^b, are 110 related diagrams in elevation and partly in section showing the controller and its driv-

ing means, Figure 3 is a diagram in elevation illustrating the relation of the controller to the safety means, whereby the emergency switch trip is operated in case of accident, Figures 4 and 5 are successive parts of a total diagram in elevation, showing the operating means for an entire system. Figure 6 is a diagram in elevation on a larger scale showing the preferred means for manual operation of the valves, and Figure 7 is a diagram in elevation of all the essential parts of a water gas set equipped with my invention.

As several of the valves which have to be moved in the operation of water gas sets, particularly in sets of large size, are very heavy, it is now the practice to employ hydraulic power to move such valves. The hydraulic cylinders or engines which supply this motive power are controlled by master valves conveniently grouped, and, in my preferred apparatus the controller is employed to control the motive means for said master valves. One preferred means whereby a master valve is thus controlled is shown in diagram in Figure 1; it being understood that the description applies to all the master valves used in my system.

In Figure 1, the front of the controller (driven preferably as hereinafter described) is shown at the right. The circular dial 10 is numbered at equal intervals around its circumference from 0 to 10, these intervals preferably representing ten minutes of time, a period longer than the total period of "blow" and run or "cycle" which is likely to be used.

The finger 11 is moved intermittently clockwise around the dial 10 at such a speed as to make the total circuit in ten minutes; and it carries a contacting member 12 which can be brought into electrical contact with successive stationary members 13 and 14, which are capable of being moved, in any well known manner, along the same circular path, so that contact with the member 12 will take place at any particular time desired. For convenience an open circle, as 13, will indicate a stationary adjustable contact member used for opening a valve, while a filled or black circle, as 14, indicates a member used for closing a valve. As will be described in connection with Figures 4 and 5 the plurality of instrumentalities for operating a gas set is controlled from one controller, by using stationary adjustable contact members in separate concentric circles, each circle corresponding to a single instrumentality. This arrangement is preferred, but is not, of course, essential.

In Figure 1, a hydraulic master valve is indicated at 15. The moving part of the valve is, as usual, operated by the rod 16, pivoted at 17 to the handle 18, which is

in turn pivoted at 19. This is for hand operation.

The preferred means for automatic operation of each valve comprise the following elements. The upper end of each operating rod 16 is pivotally connected, through the connecting rod 16^a, with the lower half of the eccentric strap 20, within which is closely fitted the eccentric disk 21. This disk is eccentrically and loosely mounted upon the shaft 22, which is continuously rotated by the motor hereinafter referred to in connection with Figures 4 and 5.

A clutch member 23 is slidably mounted on the shaft 22 and is keyed thereto, so as always to turn with it. When forced to the left in Figure 1 in the manner described hereinafter, the member 23 makes frictional engagement with the clutch disk 24, which is fixed to the disk 21, thus causing this latter to revolve with the shaft 22. By causing successive engagements of the clutch members of suitable duration, the disk 21 can be rotated through 180 degrees at a time, thereby causing successive up and down movements of the operating rod 16, and so opening and closing the valve 15.

These periodical engagements and disengagements of the clutch members are preferably accomplished by an electro-magnetic solenoid 25 which, when energized, lifts a lever 26 fulcrumed at 27. This acts through the bell crank lever 28 and the usual forks 29 and collar 30 to move the clutch member 23 in a well known manner. Disengagement of the clutch is accomplished by the spring 31, when the solenoid is de-energized.

In order that the rotation of the disk 21 may be limited to 180 degrees at each operation, there is fixed to one face of the disk a fiber disk 32 which bears a conducting plate shown in Figure 1^a at 33. This plate has an enlargement and is furnished with segment shaped openings, as shown, in order to cooperate as described hereinafter with the four contact brushes 34, 35, 36 and 37, to control the movements of the solenoid 25 and therefore of the disk 21.

Supposing the valve 15 to be closed, and that it is desired that it shall open when the intermittently moving brush 12 reaches the contact 13. In this position brushes 35 and 37 make contact with the plate 33 (Fig. 1^a) while the brush 34 being outside the edge of the plate and the brush 36 being over an aperture in the same, these brushes are not in circuit.

As soon as the brush 12 touches the terminal 13, the circuit will be closed from the main terminal L² by wire 38 to the finger 11 and brush 12, terminal 13, wire 39, brush 37, plate 33, brush 35, wire 40 and solenoid 25, to the other main terminal L². This

causes the disk 21 to revolve, and with it the plate 33, thus bringing the brush 36 very soon into contact with the brush 34, and short-circuiting the controller 10, and insuring 5 continuance of rotation of the disk 21 through 180 degrees, at the end of which movement the brush 36 comes over the second opening in the plate, and, as the brush 37 has left the enlargement on the plate 33, 10 the circuit through the solenoid is definitely and finally broken. This permits disengagement of the clutch, and the disk 21 stops turning. At the end of this movement, however, the enlargement on the plate 33 15 has come under the brush 34, and the solenoid will be again energized, to close the valve, when the brush 12 touches the terminal 14.

The apparatus for actuating the controller proper K is shown in Figures 2, 2^a, and 2^b. The motive force may be supplied by any constant speed motor, preferably an electric motor as indicated at 41. This motor, by appropriate gearing as shown, 25 drives the shaft 42 continuously, and at a relatively high speed. The shaft 43, upon which is mounted the controller finger 11, is normally driven intermittently from the shaft 42. This is preferably accomplished 30 by means of the one-toothed gear 44 on the shaft 42, cooperating with the pinion 45. In practice, the motor 41 is so timed that the tooth on 44 becomes operative once every fifteen seconds; although the particular period of time is, of course, not essential.

Through appropriate gearing, as shown, each revolution of the shaft 42 causes the spur gear 46 to make one fiftieth of a revolution and this gear is mounted loosely on 40 the shaft 43. In normal operation each movement of the spur gear 46 causes the shaft 43 to move the finger 11 through one quarter minute space, and forty of these movements carry the finger from the zero 45 position at the top of the dial in Figure 1 to the ten minute position shown in that figure. This arrangement is adapted to cycles of blow and run occupying ten minutes or less. Of course the system can be adapted 50 to other total time intervals by obvious means.

A double-faced clutch 47 is keyed to and slidably mounted upon the shaft 43, and this clutch is controlled by the pivoted 55 levers 48 and 49, actuated in one direction by the solenoid 50 and in the other direction by the spring 51. This spring normally holds one face of the friction clutch 47 in operative contact with the corresponding 60 clutch member on one face of the gear 46, as shown. In consequence, so long as this normal position is preserved, each forward intermittent movement of the gear 46 produces a movement forward of the finger 11.

65 On the opposite side of the clutch 47, the

shaft 43 carries a loosely mounted pinion 52, which is geared to the shaft 42, as shown, in a manner to produce a relatively rapid angular velocity in said pinion. When the solenoid 50 is energized it operates through 70 the levers 49 and 48 to cause engagement of the clutch 47 with a clutch member on the pinion 52, and the shaft 43 is thereby caused to revolve rapidly forward clockwise. The lever 48 carries an insulated bar 53, which 75 closes the switch 54, when the solenoid is actuated, for a purpose described hereinafter.

A revoluble drum switch, shown developed upon a plane at 55 in Figure 2, carries on its insulating surface two metal plates, 80 56, 57, which are adapted to close circuits respectively across the pairs of terminals 58 and 59. This drum turns with a supporting shaft upon which is also fixed the lever 60 normally supported by a pin 61 resting on 85 one of the arms of a three-armed lever 62 (see Figure 2^b). The spring 63 acts to depress the lever 60 with a quick snappy movement whenever the support at 62 is withdrawn, thereby producing a sudden 90 break of circuit at 56 and 57.

The dropping of the lever 60 is accomplished by a cam 64 fixed to the shaft 43, and so related to the finger 11 of the controller that, just as said finger reaches the zero position, the support for the pin 61 is withdrawn, thus breaking circuits at 56 and 57. Immediately afterward the cam 64 permits the spring 65 to act to restore the lever 62 to the position shown in Figure 2^b. This 100 return to normal is permitted by the lifting of the lever 60 by means of a pin 66 on an arm carried by the shaft 42, revolving anti-clockwise as shown by the arrow in Figure 2^b, which pin lifts the tip of the lever 60, 105 permitting the spring 65 to bring the supporting lever 62 under the pin 61.

In order that the energizing circuit of the solenoid 50 may be closed at a time when the pin 66 is in proper relation with the lever 60, 110 the solenoid circuit includes a pair of terminals 67 which are bridged by the insulated metal pin 68, on an arm carried by the shaft 42, a few moments after the lever 60 has been lifted. All of these operations are 115 carried on at relatively high speed, and well within the fifteen second period between normal movements of the finger 11.

In order that the finger 11 of the controller may be ready to start from zero at 120 the end of the fifteen second period which concludes a given cycle, and so that this may be done whatever the total time, within the maximum limit, occupied by the complete cycle of blow and run, a special "end of run contact" 69 is provided, the position of which on the controller dial is adjustable in any well known manner. This is so placed that, at the proper moment, the brush 12 makes contact with it, when the finger 11 125

will be promptly returned to zero within the next fifteen second period. This is accomplished as follows.

As soon as the brush 12 touches the "end of run" contact 69, a moment or two will elapse before the pin 68 closes circuit at 67, when the solenoid 50 will be energized by a circuit as follows. From main terminal L^1 through the finger 11 and brush 12 to contact 69, by wire 70, switch 67, wire 71, solenoid 50, switch 56 and wire 72 to main terminal L^2 .

Although this circuit will be almost instantly broken at 67, a branch circuit established at 54 by the action of the solenoid will preserve the circuit. The clutch 47 will at once cause the swiftly moving pinion 52 to drive the shaft 43, carrying the finger 11 forward, and, just as said finger reaches zero, the cam 64 will remove the support 62 from under the pin 61, thus opening the solenoid circuit at 56, and stopping the finger by movement of the clutch 47 back to the normal position shown in Figure 2. It will be seen that this return of the finger 11 to zero is accomplished well within the fifteen second period between normal movements of the finger, thus avoiding all waste of time.

It is, of course, sometimes desirable to shut down the apparatus and this should occur normally only at the end of a completed cycle. By use of the apparatus shown in Figure 2, the normal shut down switch 35 may be opened at any time during a run or blow, and the shutting down will be postponed automatically to the end of the cycle.

The normal shut down switch 73 closes circuit to the motor 41, through wires 74, 40 75 and 72, but, so long as the drum switch 55 is in the position shown, which keeps the solenoid 50 prepared, the motor 41 will be supplied with current by a branch circuit including the wire 76 and the switch 57. Hence, on opening circuit at 73, the motor 41 will go on running until the lever 60 is dropped and the drum switch 55 is operated to de-energize the solenoid 50. As already explained, this only occurs at the end of a cycle.

Before referring to the complete organization shown in Figures 4 and 5, reference will be had to Figure 3, which illustrates the automatic and the manually operated emergency apparatus whereby the entire system can be at once placed in safe condition, in case of accident, without waiting for the end of the cycle.

Assuming that the hydraulic cylinder 79^a in Figure 3 operates (for instance) to open the carburettor valve 79^b, which by some accident fails to close when the brush 12 reaches its closing terminal 14. Each of the hydraulic cylinders is connected for interlocking purposes with a revoluble drum cir-

cuit-controller 77, the various arrangements of which are fully shown in diagram in Figures 4 and 5. In Figure 3 this circuit controller is shown in end view and only the contacts associated with the emergency shut down are shown. Circuit is closed at the circuit controller 77 when the main valve is open, but as the valve closes, a rod 78, attached to the rod 79 moving with the valve, operates through a pin 80 on the forked lever 81 to open the circuit at 77.

Associated with each operating contact, as 14, on the main controller is an emergency contact 82, so placed as to be touched by the brush 12 as soon as it leaves the corresponding contact 14. Consequently if the main valve intended to be closed when contact occurs at 14 should fail to operate, circuit will be closed at 82 to shut down the whole system, as follows.

From the terminal L^1 by wire 83 to the emergency switch 84, by wire 85 to finger 11, brush 12, contact 82, wire 86, switch 77, wire 87, the high voltage coils of a transformer 88, and back to terminal L^2 . Current from the low tension side of the transformer will then energize the releasing magnet 89 which withdraws the latch 90 from the pivoted bar of the emergency switch, allowing the spring 91 to throw the switch down to close circuits through the lower stationary contacts shown in Figure 3. As will be seen from inspection of the circuits in Figures 4 and 5, this operation of the emergency switch will act to open the stack, if closed—close the generator and carburettor blast if open—open the upper hot valve if closed—and closed the oil valve if open. This places the set in a safe condition until the trouble can be located and repaired.

Inasmuch as the circuit of the motor 41 that runs the controller proper is opened when the emergency switch is thrown, the finger 11 will stop in a position to indicate at once which valve has failed to work, and so locate the difficulty.

It is desirable that an alarm bell should be rung when the emergency switch is automatically thrown, and this is accomplished as follows. Current from L^1 goes by wire 92 and wire 93 to switch 94 to a bell 95 and thence by wire 96 to the terminal L^2 .

In order to permit instant shut down by manual operation, a spring-pressed rod 97 is used which, when pushed, swings the pivoted lever 98, thereby tripping the latch 90 and throwing the emergency switch. In order to prevent ringing of the alarm bell on manual shutting down, the lever 98 carries a hook 99 which normally holds the pivoted lever 100 in the position shown, thereby keeping the plug switch 94 closed. When this hook is depressed, however, on pushing the rod 97, the spring 101 draws the lever 100 to the right and opens

the switch 94, thus opening the bell circuit. An extension 102 on the lever 100 is supported by the lever of the emergency switch, so that the lever 100 will be reset when the lever 84 is reset by hand.

For the sake of cleanliness, certain parts of the total system of circuits used in practice have been isolated in the foregoing description, and these are sufficient for the 10 normal operation of a practical system, assuming that no accidents occur. In actual operation, of course, accidental failure of operation in one member or another of the entire system must be foreseen and provided 15 for. In some cases, such a failure of operation would result in serious damage and even possible loss of life, and, for this reason, I prefer to make what may be termed an "interlocking" system, whereby accidents of this kind are automatically and certainly prevented. Such a system is shown in Figures 4 and 5, which should be placed end to end with Figure 5 on the right hand.

The controller dial and pointer hitherto 25 described has been reduced to its simplest terms, in its relation to control of a single valve. As shown in Figure 5, however, this element is shown in complete form as used in actual practice in the control of a gas set. 30 Here the finger 11 carries a brush 12 comprising five springs moving over as many concentric circles. In each of these circles is shown a series of adjustable stationary contacts corresponding to the typical contacts shown at 13 and 14 in Figure 1. Each operating contact is shown accompanied by an emergency stop contact corresponding to that shown at 82 in Figure 3.

In order to make the present invention 40 clear with relation to the complete set, including the interlocking feature, it will only be necessary to follow in detail one operation. Figures 4 and 5 show the detailed circuits for carrying out all the operations 45 in their interlocked relation as hereinafter set forth.

The various valves with their interlocking switches are shown as follows in Figures 4 and 5. The stack operator is shown at A; 50 the upper hot valve at B; the generator blast at C; the carburetter blast at D; and the oil valve at E. It is to be understood that the steam valve is automatically opened and closed by the respective closing and 55 opening of the stack. This is the usual arrangement in these sets and is not herein shown. Also the upper and lower "hot valves" are connected in the usual manner, so that when either is closed the other is 60 opened. The automatic actuating means for the elements shown at A to E are respectively indicated at A¹, B¹, etc. Their operation has been described in connection with Figures 1, 1^a and 1^b. The common shaft 22

for actuating all of these is driven by the 65 electric motor 103.

Referring now to one example of operation, let us suppose the finger 11 to stand at zero, at the beginning of a cycle, with the movable contacts 12 touching the stationary 70 contacts 104 and 105. The circuit through 104 may be traced as follows. From terminal L¹ through the switch L³ by wire 106 to switch 84, by wire 107 to switch 55 by wire 108 to switch L⁴, hereinafter described, 75 by wire 109 to switch 84, by wire 110 to switch L⁵, hereinafter described by wire 111 to the finger 11, brush 12, contact 104, wire 112, interlocking switch at E, closed when the oil valve is closed, wire 113, to plate 33 80 at A¹, the stack, solenoid 25 at A¹, wire 114, switch L⁶, wire 115, and switch L³ to L². This opens the stack as already described with relation to Figure 1. From the foregoing it is clear that the stack valve could 85 not have been opened unless the oil valve was closed.

At the same time the current from L¹, reaching the finger 11, passes by contact 105, wire 116, switch L⁴, wire 117, interlocking switch at B, when valve B³ is open as shown, by wire 118 to plate 33 at C¹, solenoid 25 at C¹, and by wire 114 as before to switch L³ and terminal L². This circuit opens the generator blast valve C³. It should 90 be noted that the generator blast valve could not have been opened unless the hot valve was closed.

By following the circuits shown in Figures 4 and 5, it will be seen that the following operations follow in order as the brushes 100 12 successively reach the contacts about to be named.

The stack and generator blast valves A³ and C³ having been opened at contacts 104 105 and 105 as above described, contact is made at 119, which acts to open the carburetter blast valve D³. It will be seen that the carburetter blast valve cannot be opened unless both the stack valve and the hot valve, and therefore the generator blast valve, have 110 been opened. These remain open during the "blow", together with the upper hot valve B³ which was left open after the previous cycle of blow and run. This "blow" 115 lasts until the contacts 12 touch the fixed terminals 120, 121, 122, and 123 when the following operations take place.

Current through 121 closes the carburetter blast valve D³; through 122 closes the generator blast valve C³; through 123 closes the stack A³; and through 120 opens the oil valve E. These operations inaugurate the "run". It is this condition which is illustrated in Figures 4 and 5. The order of these 125 operations is determined by the interlocking switches.

When the brush 12 reaches 124 a circuit is

closed which closes the upper hot valve B^3 , thereby automatically opening the lower hot valve not shown and reversing the direction of flow through the fuel. This condition continues until the terminal 125 is reached, when the circuit thus established reopens the upper hot valve B^3 .

The circuit established upon making contact at 126 closes the oil valve E, and when 10 127 is reached the resetting operation hitherto described with relation to Figure 2 takes place. This returns the finger 11 to zero for a new cycle.

If desired a contact 128 may be provided 15 as shown, whereby the generator blast valve C^3 is opened when the resetting contact is made. This affords a few moments of "purging" before the stack is opened, thus saving gas. For this purpose contact 128 20 is directly connected with contact 105 by wire 116, Figure 5, as shown.

For interlocking purposes, and to prevent 25 accidental disturbance of the proper order of operations, each valve A, B, C, D, and E is provided with a proper drum controller or switch indicated in diagram in Figures 4 and 5 by the several groups of mutually insulated brushes shown at A^2 , B^2 , C^2 , D^2 and E^2 moving over stationary conducting 30 strips whose mutual relations are shown developed upon a plane, for greater clearness. It will be seen that, by using this system, the operation of a given member must be not only begun but completed before the next 35 interlocked operation can take place.

Moreover, it is a very important feature of the present invention that, in case any one of the valves fails to complete its appropriate movement at any time, means are 40 provided whereby this very fact will cause the entire set to be brought automatically into a safe shut down condition.

Assuming, for instance, that the stack 45 valve A^3 fails to open completely when contact is made by a brush 12 at the contact 104 in the central controller switch. As soon as the brush 12 leaves the contact 104 it will close circuit upon the corresponding emergency contact 82, as follows:—see Figures 4 50 and 5.

From the main terminal L^4 , through the switch L^3 , wire 106, switch 84, wire 110, switch L^5 , wire 111, arm 11, brush 12, contact 82, wire 86, switch A^2 , common emergency wire 87, switch L^6 , primary coil 88 of the automatic shut down switch, wire 96, and through the switch L^3 to the main terminal L^2 .

The coil 88 will thus generate current in 60 its secondary winding, thereby energizing the magnet 89, and throwing the shut down switch 84, to place the set in safe shut down condition, as heretofore described. Similar action will follow the failure of any valve 65 in the set to function completely, since each

valve-operating contact in the central controller is accompanied by a corresponding emergency contact 82, properly connected to accomplish the automatic shutting down of the set.

By inspecting the circuits shown in the drawing, it will be seen that they are so interrelated through the switches at A^2 , B^2 , etc., that the following orders of operations are insured.

The oil valve must close before the stack valve opens. The stack valve must close before the oil valve opens. The hot valve must be opened before the generator blast valve will open. The hot valve and the stack valve must open before the carburetter blast valve will open. The generator blast valve and the carburetter blast valve must both close before the stack valve will close.

The carburetter blast valve must close before the generator blast valve will close. These interlocks insure both safety and correct sequence of operation.

It is desirable at times to make a straight up run; that is, to make a run without reversing the hot valves and this is usually done for one or more runs after charging the fire with fresh fuel. This can be accomplished by opening the all up run switch L^4 which is placed in the circuits of the contact 124 and its associated emergency contact. As the contact 124 is the contact for closing the upper hot valve it is obvious that when the switch L^4 is opened the hot valve will not close and the emergency contact immediately following and associated with the contact 124 is rendered inoperative. When normal runs are desired in which the flow through the fire is reversed the switch L^4 is closed.

By inspecting the circuits shown in the drawing Fig. 5 it will be seen that the circuits from the contacts 105 and 119 for opening the generator and carburetter blast valves respectively pass through the normal shut down switch L^4 , when this switch is opened, therefore, for the purpose of shutting down the set at the end of the run these valves will not open when the brush 12 reaches the zero position and the set shuts down.

The main switch L^3 is associated with a "no voltage alarm" comprising a bell 129 which rings when current fails in the magnet 130, the coils of which are constantly in the main circuit. This is a well known device for making it known when there is an accidental failure of current. When this occurs, the engineer in charge can complete the cycle by manual operation of the hydraulic valves.

Occasions may arise when it may become desirable to carry the set through one or more cycles of operation involving time intervals not in accordance with the usual

normal operation as established by the particular arrangement of fixed contacts existing in the controller 10. In order to be able to do this conveniently without having to disturb the normal condition of said controller, it is preferred to connect up with the system a special manual operator shown in its proper electric connection but on a small scale at F in Figure 5. This will now be described with reference to Figure 6 which shows the preferred construction in detail and on a larger scale.

This manual operator comprises a row of push buttons G, each cooperating in a well known manner with one of the pairs of spring contacts in the group shown at H to close its appropriate circuit. One spring in each pair is connected as shown with a common wire 131 leading to one side of the switch L⁵. The remaining springs in the various pairs H are connected, as shown in Figure 5, to wires leading to the various operating groups A, B, C, etc. In other words, these springs correspond in the manual controller to the various fixed contacts in the automatic controller 10. The buttons are shown white and black alternately. The white buttons serve for opening the different valves and the black buttons for closing them. The first pair of buttons, starting at the left in Figures 5 and 6, controls the stack valve; the next pair controls the upper hot valve; the next the generator blast valve; the next the carburetter blast valve; and the last pair controls the oil valve.

This apparatus is contained in a box furnished with a hinged cover 132, fastened in any desired manner, and, when closed, preventing access to the buttons G. In order to prevent both the automatic and the manual systems being available at the same time, the normal shut down switch takes the form shown at L⁴, having its operating handle extending through a slot in the top of the box, and being furnished with a pin 133 which engages an extension on the cover 132. This locks the cover when the switch L⁴ is closed. Within the box there is a pivoted bar 134 drawn upward by the spring 135, but depressed as shown when the cover 132 is closed by means of a rod 136 upon which the extension on the cover descends.

The switch L⁴ having been thrown to shut down the automatic system, and the cover 132 being raised, the bar 134 moves upward until the pin 137, which it carries, comes behind the switch lever L⁵, see dotted lines in Figure 6. This prevents closure of this switch as long as the cover 132 is raised.

The two-way switch L⁵ within the box normally keeps the wire 111 connected with the wire 110 going to the main terminal L¹, and thus keeps the automatic controller in operative condition. This switch is kept closed for this purpose by a rod 138 which

is pressed down by the cover 132 when closed. As soon as the cover is lifted, however, the spring 139 throws the switch L⁵ up, and the wire 110 is brought into connection with wires 140 and 131. Since the wire 140 is connected directly to the "end of run" contact 127, the effect of this upward movement of the switch L⁵ is the same as that resulting from contact between a brush 12 with the terminal 127 during normal operation of the controller 10. Therefore the controller finger 11 returns at once to zero without sending current to any of the dial contacts in passing.

At the same time, since the wire 131 is connected to one side of each pair of springs in the group H, the connecting of this wire with L¹ by the upward movement of the switch L⁵ makes it possible to close circuit through any one of the valve operating systems A¹, A², etc., by pushing the appropriate button in the group G.

It will thus be seen that, by throwing the switch L⁴, thus unlocking the cover 132, and then raising this cover, the switch L⁴ is locked and the switch L⁵ acts automatically to return the main controller 10 to zero, and to place in operative condition a group of push buttons G whereby the entire set can be operated manually in accordance with any desired time schedule. Closing of the cover disconnects the manual apparatus, connects the main controller finger 11 to the main terminal L¹ by wires 111 and 110, and unlocks the shut down switch L⁴, which can then be returned to normal, in which position it locks the cover 132.

The apparatus thus far described is capable of use in many forms to adapt it to various arrangements of the essential elements of a water gas set. By way of example I have shown one arrangement of such a set to which my invention may be applied in Figure 7. This is strictly a diagram in which practical relative proportions and locations are not followed, as these would take up too much room. It is to be understood that the various elements are shown only in their functional relation in this drawing.

The generator is shown at 142, and the carburetter 143 is shown connected to both the top and bottom of the generator by the pipes 144 and 145 respectively. Communication through these pipes is commanded respectively by the upper hot valve B and the lower hot valve 146. These are actuated as usual by the hydraulic engine B¹ through the levers and linkage shown, so that when one valve is open the other is closed; and the same mechanical transmission operates the lever 147 to operate the steam reversing valve 148, which determines the direction in which the steam is to pass through the generator in a well known way. The actual

admission of steam through the pipe 149 is governed by a hydraulic engine 150 moving a valve 151, which engine is controlled in a well known manner from the proper valve 5 in the master valve group M. This operates in conjunction with the stack valve as already described.

At 152 is shown the admission pipe for the air blast, which is controlled by the 10 carburetter blast valve D and the generator blast valve C respectively as already described.

At 153 is shown the superheater connected with the carburetter 143 by the pipe 154. 15 At 155 is shown the pipe which leads the gas to the wash box (not shown) and the remainder of the gas works with which this invention is not concerned. The stack valve A is governed by the hydraulic engine A³ 20 as already described.

At A², B², C² and D² are shown the electric interlock switches already described. These, as shown, are operated directly from the main valves and the wires shown in 25 Figures 4 and 5 are carried in conduits 214 (so marked on Figure 7) to a proper distribution box 156.

The master valves which govern the main valve-operating hydraulic engines as already described are shown grouped at M. 30 One of these operates the oil valve E directly, as shown, and as already described.

The lines representing the hydraulic piping connecting the various master valves 35 with the main valve engines are so marked on the drawing.

The electric motor for actuating these master valves is shown at 103. The switch L⁴ has been described in connection with 40 Figures 4 and 5.

The main controller for the electric circuits is indicated in Figure 7 at K, and the wires communicating therewith and shown in detail in Figure 5 are carried in a conduit 157, leading to the distribution box 156.

Various changes may be made in this apparatus without departing from the scope of the invention, which is not limited to the details herein shown and described.

50 What I claim is—

1. An automatically controlled gas apparatus comprising main operating valves, motive means for the same, an electro-magnetic operating device for each of said motive means, a controller switch having contact members electrically connected with said devices; in combination with motive means adapted to impart a cycle of movement to said switch, said motive means being adapted to impart to the movable member of the controller either an intermittent movement or a continuous return-to-zero movement, electro-magnetic shifting means for determining which of these two movements is imparted, and circuits controlled by special

contacts in the controller switch for operating said shifting means.

2. An automatically controlled gas apparatus comprising main operating valves, motive means for the same, an electro-magnetic operating device for each of said motive means, a controller switch having contact members electrically connected with said devices; a shut-down switch, electro-magnetic motive means therefor and an operating circuit for said motive means controlled by special contacts in the controller switch. 70

3. An automatically controlled gas apparatus comprising main operating valves, motive means for the same, an electro-magnetic operating device for each of said motive means, a controller switch having contact members electrically connected with said devices; a shut-down switch adapted to cut out the movable member of the controller switch and close circuits around the controller for shutting down the apparatus by suitable operation of the main valves, electro-magnetic motive means for said shut-down switch, and an operating circuit for said motive means controlled by special contacts in the controller switch. 80

4. An automatically controlled gas apparatus comprising main operating valves, motive means for the same, an electro-magnetic operating device for each of said motive means, a controller switch having contact members electrically connected with said devices; in combination with a manual operator for the apparatus comprising a series of circuit closing keys adapted respectively to close circuits for the different valve operators around and independent of the controller switch. 90

5. An automatically controlled gas apparatus comprising main operating valves, motive means for the same, an electro-magnetic operating device for each of said motive means, a controller switch having a single movable contact member and stationary contact members adapted to make operative contact with said movable member in various positions capable of regulation by an operator at will. 100

6. Apparatus as in claim 5 wherein the timing of the controller switch contact corresponding to operation of one or more valves may be changed without affecting the timing of the other valves. 110

7. An automatically controlled gas apparatus comprising main operating valves, motive means for the same, and an automatic controller for determining the time of operation of each motive means, said controller being adapted to be adjustable with respect to the timing of any one motive means without affecting the timing of another. 120

8. An automatically controlled gas appa- 130

- ratus comprising main operating valves, means for actuating said valves at predetermined time intervals, and means operating automatically upon failure of a valve 5 to operate to shut down the gas apparatus, said means being adapted to insure a safe shut down condition by automatically controlling the order in which the valves are operated.
- 10 9. An automatically controlled water gas set comprising a generator, blast valve, a carburetter blast valve and circuits for operating the same; a main controller switch having means for normally closing circuits 15 for opening said blast valve when the controller is in zero position, and an external shut down switch adapted to open said blast-opening circuit when the switch is used to shut down the set.
- 20 10. An automatically controlled gas apparatus comprising main operating valves, motive means for the same, and a plurality of interlocking means for insuring operation of said valves in a pre-determined order, 25 said interlocking means being adapted to be operated each by means directly connected with its corresponding main operating valve.
11. An automatically controlled gas appa-
- ratus comprising main operating valves, motive means for the same, an electro-magnetic operating device for each of said motive means, and interlocking switches in circuit with the electro-magnetic operating system adapted to insure operation of said main valves in a pre-determined order, said switches having their respective movable members directly and operatively connected with the corresponding main valves of the apparatus. 40
12. An automatically controlled gas apparatus comprising main operating valves, motive means for the same, an electro-magnetic operating device for each of said motive means, a controller switch having operating contact members electrically connected with said devices, emergency contacts in said controller switch corresponding respectively to said operating contact members, a shutting down circuit in which said emergency 50 contact members are adapted to be included, and switches controlled by the movements of said main operating valves for governing the operation of said shut down circuit. 45

In testimony whereof I have hereto set 55 my hand on this 20th day of December, 1921.

JAS. S. KENNEDY.
